APPARATUS FOR TREATING HYDROCARBONS TO OBTAIN HIGH GRADE LUBRICATING OILS AND LIGHTER HYDROCARBONS

William L. Gomory, Paris, France, assignor to Standard Oil Development Company, a corporation of Delaware

Application September 19, 1930, Serial No. 482,919

1 Claim. (Cl. 196—78)

This invention relates to the treatment of hydrocarbons to obtain high grade lubricating oils and lighter hydrocarbons and provides a process and apparatus whereby hydrocarbon oils of the most varied composition can be successfully treated in a continuous operation.

According to my invention the hydrocarbons are subjected in a heating and converting zone to the action of an excess amount of hydrogen or hydrogen containing gas or gas capable of liberating hydrogen or in the presence of substances capable of liberating hydrogen or hydrogen containing gas or gaseous hydrocarbons and in the presence or absence of catalysts.

All of these alternatives, either singly or in any desired combination will be hereinafter referred to as "hydrogen".

The heating and converting zone may consist of a heating coil in connection with one or more conversion chambers or it may consist of a coil which forms a combined heating and converting zone, as described in my co-pending applications Serial Nos. 475,099 and 475,100, filed August 13, 1930 now Patents Nos. 1,933,108 and 1,934,056 respectively.

In hydrogenating hydrocarbons for the production of lubricating oils great care has to be taken that the temperatures used are not too high.

The hydrogenated oil is extremely sensitive to heat treatment, therefore it is very important to exactly regulate the temperature.

According to my invention, temperatures within the range of 500 degrees F. and 800 degrees F., but preferably within the range of 550 degrees F. and 700 degrees F. are used depending upon the nature of the oil to be treated and the oil is maintained in the conversion zone for the necessary length of time under regulated temperature conditions.

Should the temperature unduly rise in the conversion zone on account of the exothermic character of the reaction, the temperature of the contents of the conversion zone can be controlled by introducing regulated quantities of charging oil or intermediate hydrogenated products from the system into the conversion or hydrogenating zone.

Such cooling medium can also be introduced into the last section of the heating coils at any convenient point.

The regulation of the temperature in the conversion zone can also be accomplished by passing the cooling medium through cooling coils located in the conversion or hydrogenating zone.

The products under conversion are kept in vehement motion in the conversion zone by agitators or preferably by withdrawing the material from the conversion chamber and circulating it back to the conversion chamber.

The hydrogenated products from the heating and converting zone are discharged into a vaporizing zone in which a low absolute pressure is maintained.

Due to the relatively low temperature used in 10 hydrogenating and the low absolute pressures maintained while distilling the hydrogenated products, very valuable lubricating oils are obtained.

The vapors obtained in the vaporizing zone 15 are subjected to fractional condensation at a low absolute pressure and the various fractions are separately recovered and removed through cooling coils into receivers in which a low absolute pressure is maintained.

The uncondensed gases together with the excess hydrogen are passed through an absorber in which the recoverable light products are absorbed with absorbent liquids such as, for instance, a gas oil of narrow boiling point range. 25

The gases which have not been absorbed in the absorber are conducted through a purifier to remove impurities such as, for instance, hydrogen sulfide and purified hydrogen is returned to the hydrogenating system.

The unvaporized residual oil is withdrawn from the vaporizing zone through cooling coils into receivers in which a low absolute pressure is maintained.

According to a modification of my process the 35 heaviest condensate is withdrawn from the bottom of the first fractional condenser or dephlegmator into an accumulator tank from which it is introduced, preferably through reheating tubes, into a vaporizing zone which is maintained 40 under a preferably lower absolute pressure than that prevailing in the first mentioned vaporizing system.

The unvaporized residual oil withdrawn from the first mentioned vaporizing zone is collected 45 in an accumulator from which it is introduced, preferably through reheating tubes, into a vaporizing zone in which a low absolute pressure is maintained preferably below that which prevails in the second mentioned vaporizing system.

In subjecting the heavier condensates withdrawn from the fractional condenser or dephlegmator of the first mentioned vaporizing system to vaporization, the unvaporized residual oil is preferably circulated from the vaporizing zone 55

through the reheating tubes back into the vaporizing zone.

Furthermore, this unvaporized liquid can be conducted into the accumulator in which the unvaporized residual liquid oil from the first vaporizing zone is collected for further vaporization under lower absolute pressure conditions.

In subjecting the unvaporized residual oil to vaporization under very low absolute pressure conditions, this residual oil is preferably circulated from the vaporizing zone through the reheating tubes back into the vaporizing zone.

The vapors obtained from the second and third mentioned vaporizing zones are fractionally condensed and separately recovered as valuable lubricating oil fractions.

In cases where the hydrocarbons to be treated contain valuable light fractions, the hydrocarbons to be treated are first subjected to vaporization in order to remove the valuable light fractions contained therein and the residue obtained in this vaporization step is subjected to the action of "hydrogen" in the heating and converting zone.

The light vapors obtained in this vaporizing step are either introduced together with the hydrogenated products into the above mentioned first vaporizing zone or these vapors can be fractionally condensed in a separate fractional condenser and recovered separately after proper cooling.

In order that the invention may be fully understood reference will be made to the accompanying drawings which illustrate in diagrammatic form with parts in section, preferred apparatus for carrying out my improved process into practice.

Figure 1 illustrates diagrammatically one form of apparatus for carrying out my improved process.

Figure 2 shows a modification of the apparatus shown in Figure 1, wherein means are provided for separating excess hydrogen prior to subjecting the conversion products to vaporization.

The oil to be treated is drawn from any convenient source of supply 1 by means of a pump 2 and is forced through line 3 into preheating coil 4 located in the upper section of fractional condenser or dephlegmator 5, the oil then passing through line 6 into furnace coils 7.

The furnace coils 7 comprise three pipe sections 8, 9 and 10. The pipe section 10 of the furnace coils 7, which may be of larger diameter than the pipe sections 8 and 9, may contain suitable hydrogenating catalysts.

The furnace coils 7 may advantageously be built of a series of straight pipes in accordance with standard practice e. g. with the ends of the pipes extending through the flue walls and suitably connected by headers having apertures provided with removable plugs to permit inspection of the pipes and to insert and remove the catalytic material.

"Hydrogen" is withdrawn from a suitable source of supply 99 by means of a pump 100 and is passed through line 101, preferably through a heating coil 101' which is heated in any suitable manner. The heated "hydrogen" is passed through main-line 102, through line 103 to the inlet end of the furnace coils 7 where it mixes with the oil passing through the coils.

"Hydrogen" can be also introduced from the main-line 102 into the furnace coils 7 at various intermediate points and into the outlet thereof through lines 104 and 105.

The mixture of heated oil and "hydrogen" from

the furnace coils 7 passes through line 11 and thence through line 12 into the thermally insulated conversion chamber 13 from which the products are withdrawn through lines 14 and 15 and pressure-reducing valve 16 and thence pass into vaporizer 17.

In the drawings only one conversion chamber is shown but any number of conversion chambers can be used either in series or in parallel.

"Hydrogen" is introduced into the conversion chamber 13 from the main-line 102 through line 106.

The catalysts employed may be spread on perforated trays or suitably disposed within the chamber, as shown at 13'.

In certain cases the use of the conversion chamber can be dispensed with and then the hydrogenating treatment is carried out in the furnace coils 7.

In general the hydrogenating treatment of the oil may be carried out according to the various steps described in my co-pending application above referred to, except that the temperatures to be used are lower to enable to produce high grade lubricating oils.

The oil to be treated is heated in furnace coils 7 to temperatures within the range of 500 degrees F. and 800 degrees F., but preferably within the range of 550 degrees F. and 700 degrees F., depending upon the nature of the oil to be treated and the oil is maintained in the conversion chamber for the necessary length of time under regulated temperature conditions.

Should the temperature unduly rise in the conversion zone on account of the exothermic character of the reaction, the temperature of the contents of the conversion zone can be controlled by introducing from charging line 6 through line 6' regulable quantities of charging oil into conversion chamber 13 or into coil section 10.

Intermediate hydrogenated condensates or hydrogenated residual oil can be also used for the regulation of the temperature in the conversion chamber or in the last section of the coils forming the conversion zone.

Such condensates can be introduced by pump 110 through line 110' into coil section 10 and through line 110'' into line 11 leading into conversion chamber 13.

Residual oil can be introduced by pump 53 through line 53' into coil section 10 and through line 53'' into line 11 leading into conversion chamber 13.

The regulation of the temperature in the conversion chamber can also be accomplished by passing charging oil through cooling coils 88 located in the conversion chamber 13, through line 6'.

The products under conversion are kept in vehement motion in the conversion chamber by agitators or preferably by withdrawing the material from the conversion chamber and circulating it back to the conversion chamber with the aid of pump 87 through lines 86 and 86'.

The pressures employed usually will exceed atmospheric pressure. Pressures of 100 pounds or more may be employed and higher pressures, such as for example 500 pounds to 3000 pounds or more may be used in carrying out the hydrogenating treatment.

The hydrogenated products entering the vaporizer, which is heavily insulated against heat losses, will vaporize in a greater or lesser extent depending upon the degree of absolute pressure

maintained in the vaporizer by vacuum pump 18.

The vapors are removed from the vaporizer through line 19 and pass into fractional condenser or dephlegmator 5 and thence through line 20 into condenser 5'.

Fractional condensers 5 and 5' are protected against outside variation of temperature by insulation and are provided with cooling coils 4 and 4' located in the top part of the dephlegmators, through which cooling medium (feed oil, water, etc.) can be passed to produce the necessary amount of condensation.

The fractional condensers or dephlegmators 5 and 5' are also provided in the bottom part with steam coils 21 through which live steam may be introduced, if desired, to assist in removing lower boiling fractions from the condensate accumulating in the bottom of the fractional condensers.

In the drawings two fractional condensers are shown but a greater number of such fractionators can be used.

The vapors pass from the fractional condensers through line 22 into barometric condenser 23 which is connected through line 22' with vacuum pump 18.

The gases discharged by vacuum pump 18 are passed with the booster pump 24 through line 25 to absorber 26 and from there through line 27 to purifier 28 and the excess "hydrogen" gas, after the light hydrocarbons have been absorbed and impurities removed, is conducted through line 29 and booster 30 into return-gas line 31 to be conducted to the main gas-line 102 or through line 31' to the "hydrogen" supply 99.

Any lighter product which may have been condensed by water spray 107 in barometric condenser 23 is removed therefrom through line 32 into separator 33 from which it can be recovered.

Absorbing liquid, for example gasoil, is introduced through line 34 into absorber 26 and the absorbed products are removed through line 35.

Purifying liquid such as, for instance, alkaline solution is introduced through line 36 into purifier 28 and the liquid containing impurities is removed from the purifier through line 37.

Vaporizer 17 is also provided with steam coil 17' through which live steam may be introduced into the vaporizer, if desired, to assist in the vaporization of the oil.

Sometimes it might be desirable to recover from vaporizer 17 a residual oil with certain specific composition and in order to enable to regulate the temperature of vaporizer 17 the same is provided in the top part thereof with a cooling coil 17'' through which a cooling medium, for instance feed oil, is passed to provide the desired regulation.

The residual oil obtained in vaporizer 17 is withdrawn through line 38 and line 39 and is passed through a cooler into a receiver which is connected to a vacuum pump (not shown) in exactly the same manner as the heavy condensate obtained in fractional condenser 5 is withdrawn through lines 40 and 41 through cooling coil 42 and line 43 to receivers 44. These receivers are connected through line 45 to vacuum pump 46 and can be used alternately in such a manner that one of the tanks is used to collect the condensate while the condensate is withdrawn from the other tank through line 47.

Similarly the condensate collected in fractional condenser 5' is withdrawn through line 48, cooling coil 49 and line 50 into receivers 51 which are connected through line 52 with vacuum pump 46.

The condensate formed in fractional condenser

5 and withdrawn through line 40 may be returned through line 40' into vaporizer 17.

The vaporizer and fractional condensers are maintained under an absolute pressure, for example between 15 to 50 m/m. mercury and in some cases an absolute pressure preferably less than 15 m/m. mercury is maintained.

According to a modification of my invention the residue withdrawn through line 38 from vaporizer 17 is passed by pump 53 through line 54 to 10 accumulator tank 55.

Accumulator tank 55 is provided with a vent-line 55' to allow the return to vaporizer 17 of any vapors which might be evolved in accumulator tank 55.

The residual oil collected in accumulator tank 55 is passed through line 56 by pump 57 through line 58 and preferably through reheating tubes 59 to vaporizer 60.

When the heat contained in the residual oil 20 withdrawn from accumulator 55 is not sufficient and the oil is passed through reheating tubes 59, the oil is heated therein to a temperature which is close to and preferably somewhat below the mean boiling point of the fractions contained in the residual oil.

The oil entering vaporizer 60 will vaporize at a greater or lesser extent depending upon the absolute pressure which is maintained in vaporizer 60 and the fractional dephlegmators 61 30 and 61'. This absolute pressure is preferably lower than that maintained in vaporizer 17 and fractionators 5 and 5'.

Vaporizer 60 is properly insulated to avoid heat losses.

Vaporizer 60 is provided with steam coil 60' through which live steam may be introduced into the vaporizer 60, if desired.

Sometimes it might be desirable to recover from vaporizer 60 a residual oil with certain specific composition and in order to enable to regulate the temperature of vaporizer 60, the same is provided in the top part thereof with a cooling coil 60'' through which a cooling medium, for instance feed oil, is passed to provide the 45 desired regulation.

The residual oil collected in vaporizer 60 can be withdrawn through lines 62 and 63 through cooling coils 151 into receivers 152 (only one receiver shown) which are connected with a vacuum pump 153, in exactly the same manner as described above.

All the residual oil collected in vaporizer 60 can be recirculated through line 62, pump 64, line 65, through reheating tubes 59 into vaporizer 60.

The vapors obtained in vaporizer 60 are led through line 66 into fractional dephlegmator 61 in which valuable lubricating oil fractions are obtained.

The vapors from fractional dephlegmator 61 60 pass through line 67 into fractional dephlegmator 61' in which further lubricating oil fractions are obtained.

Fractional dephlegmators 61 and 61' are insulated against the influence of outside temperature variations and are provided with cooling coils 84 through which cooling medium (feed oil, or other oil, or water, etc.) is passed to cause the necessary degree of cooling and they are also provided with steam coils 85 through 70 which live steam may be injected, if desired.

In the drawings two fractional condensers are shown but a greater number of such fractionators can be used.

The vapors leave fractional dephlegmator 61' 75

and pass through line 68 into barometric condenser 69 which is connected to vacuum pump 70 through line 70'. The function of barometric condenser 69 is identical with that described in 5 connection with barometric condenser 23.

The lubricating oil fraction obtained in fractional dephlegmator 61 is withdrawn through line 71, cooling coil 72, line 73 into receivers 74 which are connected through line 75 to vacuum 10 pump 76.

The lubricating oil fraction obtained in fractional dephlegmator 61' is removed through line 77, cooling coil 78 and line 79 into receivers 80 which are connected through line 81 to vacuum 15 pump 76.

Receivers 74 and 80 are used in such a manner that one of the receivers 74 and 80 respectively is used to collect lubricating oil fractions while the liquid is removed from the other receivers through lines 82 and 83 respectively. 20

According to a further modification of my process, the condensate obtained in fractional condenser 5 and removed through line 49 is passed by pump 110 into accumulator 111. Accumulator 111 is provided with vent-line 111' to allow the return to vaporizer 17 of any vapors which may be evolved in accumulator 111.

The condensate is conducted from accumulator 111 through line 112 by the aid of pump 113, 30 through line 114 and preferably through reheating tubes 115 into vaporizer 116.

When the heat contained in the condensate withdrawn from accumulator 111 is not sufficient and the oil is passed through reheating tubes 35 115, the oil is heated therein to a temperature which is close to and preferably somewhat below the mean boiling point of the fractions contained in the residual oil.

The oil entering vaporizer 116 will vaporize at 40 a greater or lesser extent depending upon the absolute pressure which is maintained in vaporizer 116 and the fractional dephlegmators 117 and 117'.

This absolute pressure is preferably lower than 45 that maintained in vaporizer 17 and fractional dephlegmators 5 and 5', but preferably somewhat higher than that prevailing in vaporizer 60 and fractional dephlegmators 61 and 61'.

Vaporizer 116 is properly insulated to avoid 50 heat losses and is provided with steam coil 116' through which live steam may be injected in vaporizer 116, if desired.

Sometimes it might be desirable to recover from vaporizer 116 a residual oil with certain 55 specific composition and in order to enable to regulate the temperature of vaporizer 116, the same is provided in the top part thereof with a cooling coil 116'' through which a cooling medium, for instance feed oil, is passed to provide 60 the desired regulation.

The residual oil collected in vaporizer 116 can be withdrawn through lines 118 and 119 through 65 cooling coils 154 into receivers 155 (only one receiver is shown) which are connected to vacuum pump 156 in exactly the same manner as described above.

Or the residual oil collected in vaporizer 116 can be recirculated through line 118 and pump 120, line 121 through reheating tubes 115 into 70 vaporizer 116.

The vapors obtained in vaporizer 116 are led through line 122 into fractional dephlegmator 117 in which valuable lubricating oil fractions are obtained.

75 The vapors from fractional dephlegmator 117

pass through line 123 into fractional dephlegmator 117' in which further lubricating oil fractions are obtained.

Fractional dephlegmators 117 and 117' are insulated against the influence of outside temperature variations and are provided in the top thereof with cooling coils 124 through which cooling medium, for instance feed oil, is passed to cause the necessary degree of cooling and they are also provided in the bottom part thereof with 10 steam coils 125 through which live steam may be injected, if desired.

In the drawings two fractional condensers are shown but a greater number of such fractionators 15 can be used.

The vapors leave fractional dephlegmator 117' and pass through line 126 into barometric condenser 127 which is connected to vacuum pump 128 through line 128'.

The function of barometric condenser 127 is 20 identical with that described above in connection with barometric condenser 23.

The lubricating oil fraction obtained in fractional dephlegmator 117 is removed through line 129, cooling coil 130, line 131 into receivers 132 25 which are connected through line 133 to vacuum pump 134.

The lubricating oil fraction obtained in fractional dephlegmator 117' is removed through line 135, cooling coil 136 and line 137 into receivers 30 138 which are connected through line 139 to vacuum pump 134.

Receivers 132 and 138 are used in exactly the same manner as described above in connection with receiver tanks 44, 51 and 74, 80. 35

In cases where the hydrocarbons to be treated contain valuable light fractions, such hydrocarbons are treated according to a further modification of my process in which the feed oil is passed by the aid of feed pump 2 from supply tank 1 40 through line 3 and cooling coil 4 and line 6 through line 89 into still 90 in which it is spread on tray 91.

Still 90 is provided with steam coil 92 through 45 which live steam may be introduced into the oil contained in the still, and still 90 may be also directly heated.

Obviously instead of still 90 shown in the drawings, any other method (for instance a vaporizing system consisting of a heating coil connected 50 with a vapor tower) can be used in order to separate the light fractions contained in the oil to be treated.

The light fractions obtained in still 90 are removed through line 93 and are conducted through 55 lines 94 and 15 to pass through pressure-reducing valve 16' into vaporizer 17 in such a manner that these vapors are mixed with the hydrogenated products passing from the hydrogenating system into the vaporizing system. 60

The vapors obtained in still 90 can also be separately removed therefrom through lines 93 and 95 and led to a condensing and cooling system (not shown) from which the condensate can be 65 separately removed.

The unvaporized residue from still 90 is passed through line 96 and is conducted by the aid of pump 97 through line 98 into furnace coils 7 to be treated exactly in the same manner as described above. 70

Figure 2 shows another modification of my process according to which the products obtained in the hydrogenating step can be freed from all or greater part of the excess "hydrogen" and 75

the low boiling point products before subjecting the hydrogenated products to subatmospheric distillation.

In this case the hydrogenated products are discharged through line 14 from the hydrogenating system through line 170 into separator 171 in which the temperature and the pressure are so regulated that only the most volatile hydrocarbons will be vaporized and removed from the separator together with the excess "hydrogen".

The temperature in the separator can be regulated in any known manner, for instance by passing cooling medium through coils 172.

The vapors together with the excess "hydrogen" are passed from separator 171 through line 173 and line 25 through absorber 26 in which the recoverable light products are absorbed and the gases which have not been absorbed are conducted through line 27 through purifier 28 and the purified hydrogen is returned to the hydrogenating system through line 29, booster pump 30 and line 31.

The hydrogenated products freed from the excess "hydrogen" and the low boiling point products are conducted through line 174, by pump 174' preferably through reheating tubes 175 and through line 15 into vaporizer 17 which is maintained under sub-atmospheric pressure.

When the heat remaining in the hydrogenated products is not sufficient and they are passed through reheating tubes 175, they are heated therein to a temperature which is close to and preferably somewhat below the mean boiling point of the fractions contained in the hydrogenated products. The direct passage of hot hydrogenated products to a vaporizer and the subsequent treatment of the fractions vaporized therein is claimed broadly in my co-pending application, Serial No. 475,099. filed August 13, 1930 and al-

lowed April 19, 1933. The present application is directed specifically to the operation of the vaporizer at sub-atmospheric pressures and to the subsequent distillation of the vaporizer residue.

I have described and shown preferred form of the apparatus and various modifications of the use of my invention but it is to be understood that there are possible modifications without departing from the spirit of the invention and I wish to claim as broadly as it is permitted by the prior art, the invention covered in the appended claim.

I claim:—

Apparatus for the production of high grade lubricating oils, which comprises heating means and means for supplying oil under pressure to the inlet of said heating means, means for supplying heated gas rich in free hydrogen to the inlet and outlet of said heating means and to various intermediate points thereof, a fourth means adapted to maintain the oil and gas under subatmospheric pressure and at a high temperature and provided with a circulating pump connected to the bottom and top part thereof, vaporizing means into which the hot oil from said fourth means is directly discharged, said vaporizing means being adapted to be maintained at subatmospheric pressure and being provided with outlets for vapors and liquids, the vapor outlet from said vaporizing means being connected to a fractional condenser provided with liquid and vapor outlet connections, the vapor outlet connection from the fractional condenser being connected to a barometric condenser which is connected with a vacuum pump, the liquid outlet of said vaporizing means being connected by a pump to a reheating and vaporizing system, said vaporizing system being provided with means to maintain sub-atmospheric pressures therein.

WILLIAM L. GOMORY.
